Application January 29, 1940, Serial No. 316,196

24 Claims. (Cl. 33—205)

1
Our invention relates to the art of ascertaining and indicating deviations from vertical of a well bore and is applicable to well surveying devices in general. Since it is contemplated that the present invention will find immediate application in devices that may be incorporated in a string of drill pipe to serve as a deviation-warning means for the convenience of a driller, the present disclosure will be confined to embodiments of such character, but it is to be understood that our invention is not to be restricted to any narrow class of well surveying apparatus.

The unfavorable consequences, difficulties, and problems attributable to changes in direction in well bores are well known. Crookedness in bore holes results in mechanical difficulties, including breaking of drill pipe, difficulties in drilling, difficulties in running casing, and difficulties in subsequent pumping. It is not uncommon for drill holes to deviate so far as to enter the confines of adjacent properties or to cause serious damage to neighboring wells. Unfortunately, in the prevailing drilling practice the hole may be extended in the direction of deviation for a considerable distance without knowledge on the part of the driller. If the deviation is not excessive, it may be decided to suffer the consequences and to continue drilling. If the deviation is serious, however, it becomes necessary to draw back to the point of initial departure from vertical and redrill, the procedure usually involving cementing the hole for some distance. It is apparent, then, that there is a distinct and pressing need for some means to detect and evaluate any serious deviation at the very inception of such deviation.

In ordinary drilling performed with proper care, significant deviation from the desired vertical alignment is unusual and generally may be readily corrected by some simple expedient. Adequate correction may involve merely reducing the weight on the drill or reducing the rate of drill rotation or the replacement of an unsymmetrical bit. More extensive correction procedures may be necessary where caving formations allow excessive flexure of the drill pipe or where the drill is encountering faulted or dipping strata or the boundary between hard and soft formations. In any case if the required information is available to the driller promptly and as frequently as desired, the hole may be kept straight, and losses in drilling time attributable to bore deviation may be reduced to a minimum.

In designing the particular form of our invention here under consideration our general ob-

2
ject is to make known to a driller by some suitably simple procedure any serious substantial deviation of the bore hole direction, and to do so at the drilling time.

One group of objects in the invention relates specifically to the problems involved in designing such a device for operation in drill pipe. Among these objects are to achieve a rugged compact construction, to provide a structure that will not interfere with normal circulation of drilling fluids, to provide a self-contained apparatus requiring no cables or wires for communication with the surface, to provide an indicating apparatus adapted for relatively long periods of continuous service in a bore hole, and to provide a device that may be readily installed in the bore hole or withdrawn therefrom without the necessity of pulling the string of drill pipe.

In another group of objects in mind, we take cognizance of the fact that a driller is primarily concerned with drilling operations. He is not a surveying expert and moreover he is reluctant to lose substantial periods of drilling time for surveying operations. We propose, therefore, to provide a relatively simple method of ascertaining and imparting the required information without requiring highly specialized skill on the part of the driller and without straining the driller's patience. It is our object to inform the driller as often as he desires as to whether or not substantially vertical alignment is being maintained in the drilling of the bore hole and to indicate the approximate degree of any deviation, whereby the driller may be warned to check the various drilling factors when deviation occurs and may be informed promptly about whether or not the corrective steps he takes suffice to restore normal alignment of the bore hole. In other words, it is our object to meet the need for some simple foolproof warning device or warning system to fit into routine drilling operation without incurring the expense or involving the disadvantages of typical well surveying instruments. We propose to provide what is in effect an automatic indicating system that will perform promptly in some simple manner without complicated auxiliary surface equipment and without any difficult or time-consuming manipulations on the part of the driller at the surface.

Our invention includes combining with a simple deviation-detector some means for sending a signal or series of signals up the well to indicate whether or not the bore hole is within a permissible range of deviation from vertical and to

evaluate any deviation found to exist. Various signal systems and various signal mediums may be used with the detector in various practices of the invention, but preferably the signals are produced by creating pressure variations in the column of drilling mud. Certain objects of the preferred form of our invention, then, are directed to the means for creating such pressure waves under the control of the detector.

The preferred form of our invention is further characterized by the concept of employing the energy of the circulating drilling fluid to actuate the detecting and signalling means. More specifically, we have in mind employing a subterranean mechanism in the well that has an inherent tendency to move operatively in one direction and is adapted to be moved in the opposite operative direction in opposition to such tendency in response to force derived from the stream of drilling fluid. An important feature of such an arrangement is that the mechanism may be caused to reciprocate by simply shutting off normal circulation of the drilling fluid to permit the mechanism to operate in one direction and then resuming the fluid circulation to cause the mechanism to be moved in the opposite direction. The movement of the reciprocating mechanism produces a series of signals in which the number of signals varies with the extent of movement, and the deviation-detector is adapted to arrest the movement of the reciprocating mechanism thereby to vary the series of signals in accordance with the alignment of the well bore relative to vertical.

One of the specific objects of our invention is to provide a subterranean mechanism immersed in a drilling fluid that is extensible and contractile while immersed with substantially no change in the volume of the drilling fluid displaced by the mechanism. Another object is to provide a velocity control for the mechanism movement for various purposes in various forms of our invention. One such purpose is to delay the movement of the mechanism to permit the deviation-detector to become stabilized; another purpose is to accelerate the movement of the mechanism between signal points; and a third purpose is to accelerate the rate of pressure rise in the drilling fluid when pressure changes in the drilling fluid are employed for signals.

In one form of our invention the deviation-detector is in the form of a pendulum and we have the further object of automatically locking the pendulum at a gravitational position prior to arrest of the mechanism movement by the pendulum. A still further object relating to such a pendulum is to provide for automatically constraining or immobilizing the pendulum during normal drilling to avoid damage to the pendulum by the vibration and shock incidental to drilling.

The above and other objects and advantages of our invention will be apparent from the following detailed description taken with the accompanying drawings.

In the drawings, which are to be taken as illustrative only:

Fig. 1 is an axial section through a special drill stem sub incorporating the preferred form of our invention;

Fig. 2 is a similar view to indicate how a certain reversal of parts may be made in modifying the structure of Fig. 1;

Fig. 3 is a fragmentary view of the same character showing an automatic dashpot valve that may be added to the structure of Fig. 1;

Fig. 4 is a similar view to suggest how the dashpot arrangement in Fig. 1 may be altered for certain desirable dashpot effects;

Fig. 5 is an axial section through a special drill stem sub incorporating a second form of our invention;

Fig. 6 is a similar view showing a third form of the invention;

Fig. 7 is a fragmentary view of the same character to indicate how a portion of the structure shown in Fig. 6 may be modified; and

Fig. 8 is a fragmentary axial section similar to Fig. 5 to indicate how the upper structure in Fig. 5 may be modified to provide a structure in which sound signals are transmitted through the metal of the drill string.

Our invention may be enclosed in a special drill collar or sub in the drill string of a well immediately above the bit. In the particular form of our invention shown in Fig. 1, such a special drill stem sub, generally designated 10, has an enlarged upper bore 11 to retain a special sleeve insert 12, an intermediate bore 13 of somewhat less diameter to house an instrument case 14 of cylindrical configuration, and a lower bore 15 leading to the bit. The reduction in internal diameter at the lower end of the intermediate bore 13 provides a shoulder 16 to support a spider 17, the purpose of which is to seat the lower streamlined end of the instrument case 14 without blocking fluid flow past the cylinder. Fig. 1 shows the disposition of the various parts of the invention during normal drilling while the drilling fluid is flowing downwardly through the drill string to the bit. A channel of adequate cross-sectional dimension to accommodate the required flow is provided not only in the sleeve insert 12, but also around the instrument case 14.

The sleeve insert 12 has an upper bore 20 corresponding to the normal bore of a drill collar. Below the upper bore 20 the sleeve is enlarged in internal diameter, but is provided with a series of five uniformly spaced inwardly directed annular ribs 21a-21e at which the fluid channel is constricted to approximately the diameter of the upper bore 20.

The instrument case 14 is closed at its lower end and is held in a centralized position within the sub 10 by the spider 17 at the lower end of the cylinder and by centering leaf springs 22 attached to its upper end by rivets 23. The instrument case 14 provides an upper dashpot cylinder 24 and a bore 25 communicating with the lower end of the dashpot cylinder through a tapered bore 26. Below the bore 25 the interior of the instrument case forms a pendulum chamber 27 that is enlarged in successive stages to provide five relatively sharp annular stop shoulders 28a-28e of the same spacing as the previously mentioned constricting ribs 21a-21e.

Slidably mounted in the instrument case 14 is a plunger, generally designated 30, having an upper shank 31, a lower shank 32, and integral therewith an intermediate dashpot piston 33 cooperative with the dashpot cylinder 24. The end of the upper shank 31 carries a plunger head 34 having a spear projection 35, the head being small enough in diameter to clear the constricting ribs 21 of the sleeve insert 12 but being large enough to choke down the stream of drilling fluid to a material extent whenever it registers with one of the constricting ribs. A split ring 39 in a complementary annular recess in the dashpot cylinder 24 serves as a stop cooperative with the dashpot piston 33 to limit the upward movement

of the plunger. The instrument case contains a quantity of suitable liquid such as light oil that is isolated from the drilling fluid by a suitably extensive and flexible diaphragm sleeve 37. The lower end of the diaphragm sleeve incorporates an elastic ring 38 that tightly embraces the upper plunger shank 31, and the upper end of the diaphragm sleeve is attached to the surrounding dashpot cylinder 24 by a split ring 36 that crowds the material of the diaphragm into a complementary recess in the cylinder wall.

While the construction provides for extension and retraction of the plunger 30 relative to the instrument case it does not involve any change in the displacement of the drilling fluid column in which the combination is immersed. In other words, extension and retraction of the plunger involves merely change in shape of a constant displacement volume, the diaphragm sleeve 37 permitting the drilling fluid to enter the upper end of the instrument case as required to maintain the constant displacement of the combination as the plunger 30 is extended upward in the operation of the invention.

The dashpot piston 33 is provided with a dashpot passage 40 that preferably is reduced in diameter at one end to provide a sharp-edged orifice 42, the purpose of the sharp-edged orifice being to minimize variations in the rate of dashpot flow that might result from changes in viscosity of the dashpot liquid incidental to changes in temperature. Beneath the piston 33 and acting between the piston and the bottom of the dashpot cylinder 24 is a helical lift spring 43 that continuously urges the plunger 30 upward into extended disposition. The spring is not of sufficient strength to withstand normal dynamic pressure against the plunger head 34 so that during normal downward flow of the drilling fluid the plunger is in the retracted disposition indicated in Fig. 1.

Attached to the end of the lower plunger shank 32 by a pin 44 is a socket or bearing 45 for a ball 46 and from the ball depends a pendulum 47 in the form of a rod with a pendulum head 48. Other types of pendulum bearings may be employed. The lower portion of the pendulum head 48 is preferably spherical or conical to facilitate guidance of the head into a central restraining bore 49 when the pendulum is carried downward by the retraction of the plunger 30. The upper surface or rear of the pendulum head, however, is flat or concave to favor engagement of the head with one of the annular stop shoulders 28 when the pendulum is inclined during an upward or extension movement of the plunger.

The operation of the arrangement of our invention shown in Fig. 1 may be readily understood from the foregoing description. During normal drilling operation the dynamic pressure of the downwardly flowing drilling mud against the plunger head 34 keeps the plunger 30 in retracted disposition in opposition to the lift spring 43. To make a test for bore-hole deviation the driller stops rotation of the drill string and then stops the mud pumps. As soon as the driller stops the mud pumps, thereby cutting off circulation of the drilling fluid, the spring 43 becomes effective to lift the plunger 30 toward its fully extended position. If the plunger 30 is permitted to move upward to the limit determined by the stop ring 39, the plunger head 34 will reach the enlarged space above the uppermost constricting rib 21a.

The upward movement of the plunger must be smooth and relatively slow to permit the pendulum 47 to become stable at its natural gravitational position and to prevent the pendulum from being deflected by resistance of the fluid in which it is immersed. The upward movement of the plunger 30 is retarded to the required slow rate, because the fluid in the instrument case above the piston 33 must be displaced through the dashpot passage 40.

The upward movement of the plunger extends to the maximum level permitted by the stop ring 39 only if the drill stem sub 10 is substantially vertical so that the pendulum takes a gravitational position coaxial with the sub and therefore escapes even the uppermost, small-diameter stop shoulder 28a. If, however, the drill stem sub 10 is inclined away from the vertical, the pendulum head 48 will engage one of the annular stop shoulders 28.

If the deviation from vertical exceeds 4°, the pendulum will become stabilized at the corresponding inclination relative to the sub axis in the interval of a minute or more in which the pendulum head approaches the level of the lowermost annular stop shoulder 28e and the pendulum head will then engage the annular stop shoulder 28e to arrest the upward movement of the plunger 30. At this arrested position of the plunger head 34 the lower circumferential edge of the plunger head will be at approximately the level indicated by the dotted line E. If the deviation is between 3° and 4°, the pendulum head 48 will clear the annular stop shoulder 28e, but will engage the next annular stop shoulder 28d. In like manner a deviation from vertical of between 2° and 3° will cause the pendulum to be stopped by the annular stop shoulder 28c; a deviation of 1° to 2° will cause the upward movement to be arrested at the stop shoulder 28b; and if the deviation is between 1/2° and 1° the uppermost annular stop shoulder 28a will be effective. Dotted lines A, B, C, and D represent respectively arrested positions of the plunger head 34 when the pendulum head 48 engages respectively the annular stop shoulders 28a, 28b, 28c, and 28d. It is apparent that if no stop shoulder is engaged the plunger will rise to its fully extended position with the plunger head 34 above the uppermost constricting rib 21.

After stopping the mud pumps, the driller waits for an interval of sufficient duration to permit the plunger 30 to cover its maximum range of longitudinal movement. The driller then starts the mud pumps to resume the downward flow of drilling fluid, which downward flow exerts dynamic pressure against the plunger head and causes the plunger to retract toward its lowermost position. As the plunger 30 retracts at a rate limited by the described dashpot action, the plunger head 34 moves slowly past whatever constricting ribs 21 lie between its position of arrest and its normal retracted position. If the drill stem sub 10 is close enough to vertical to permit maximum upward extension of the plunger 30 the plunger head 34 on its downward movement will approach and pass the five constricting ribs 21 in succession, thereby causing the downflowing drilling stream to be retarded and released five times at substantially uniformly spaced time intervals. Even if the temporary reductions in the rate of flow of the drilling fluid are relatively mild, they may be readily detected by pressure-responsive means at the top of the well. In our preferred practice, however,

the reductions in flow caused by the plunger head cooperating with the constricting ribs are relatively severe, so severe as to cause a distinctly discernible water-hammer wave to traverse the column of drilling fluid to the surface of the well.

It is apparent that a series of five signals will indicate that the well bore is within the tolerance of $\frac{1}{2}^{\circ}$ from vertical; four signals will indicate an inclination of $\frac{1}{2}^{\circ}$ to 1° from vertical; three signals will indicate a deviation of between 1° and 2° from vertical; two signals will indicate a deviation of 2° to 3° ; one signal will indicate a deviation of 3° to 4° ; and if no signals are received the driller will be informed that the deviation is greater than 4° .

The purpose of Fig. 2 is to suggest a certain reversal of parts that may be made in the portion of Fig. 1 that periodically restricts the flow of the drilling fluid as the plunger 30 moves downward toward its normal retracted position. Fig. 2 shows a special drill stem sub 50 corresponding to the special sub 10 of Fig. 1. The special sub 50 has a sleeve insert 52 that corresponds to the sleeve insert 12, but provides only one constriction 53 instead of the five constricting ribs of Fig. 1. The rest of the arrangement is identical with the arrangement of Fig. 1, corresponding numbers indicating corresponding parts, except the plunger head 55 which comprises in effect five individual head elements 56 in one integral structure providing alternate reduced and enlarged diameters. The spacing of the head elements 56 longitudinally of the plunger 30 is the same as the spacing of the constricting ribs 21 of Fig. 1 so that as the plunger head 55 descends, it cooperates with the sleeve insert 52 to throttle the flow of the drilling fluid in the same manner as achieved by the arrangement in Fig. 1.

Fig. 3 suggests the addition to Fig. 1 of a valve member 58 in the form of a collar slidably mounted on the lower plunger shank 32 to close the dashpot passage 40 at least partially whenever relatively high mud pressure on the plunger head 34 at a flow-constricting position of the plunger head tends to accelerate the downward movement of the plunger 30. The collar rests on the upper end of the previously mentioned lift spring 43 and is normally maintained at a position slightly spaced below the piston 33 by a second spring 59 that is somewhat stronger than the first spring 43. The spring 59 rests upon the valve member 58 and embraces a downward extension 60 of a dashpot piston 61. Except for the substitution of the piston 61 for the piston 33 and the addition of the valve member 58 and the second spring 59, the arrangement suggested by Fig. 3 is identical with the arrangement shown in Fig. 1.

The valve member 58 in Fig. 3 is normally held in spaced relation to the piston and does not interfere with the operation of the plunger. Whenever a rise in pressure at a flow-constricting position of the plunger head causes the piston 61 to accelerate sharply the piston moves against the valve member 58 because the valve member is retarded both by its own inertia and by its own effect in restricting flow past its periphery. The valve member 58 closes or partially closes the lower end of a dashpot passage 62 in the piston 61 that corresponds to the dashpot passage 40 in the piston 33. As a result of this arrangement the dashpot passage 62 is automatically throttled whenever relatively high pressure builds up sufficient to tend to accelerate sharply the downward movement of the plunger 30. The virtue of such

an arrangement is that the plunger may be designed for rather rapid travel between signals, the valve member 58 being relied upon to retard the plunger travel automatically at the flow-constricting position of the plunger head. The addition of the valve member 58 prolongs the signal periods of high pressure and accelerates the pressure rise at each of the constricting positions of the plunger head.

Another manner in which the arrangement of Fig. 1 may be modified to accentuate the pressure signals by automatically controlling the movement of the plunger 30 may be understood by referring to Fig. 4. This particular modification involves substituting a new piston assembly for the piston 33 of Fig. 1 and involves the provision of by-passing recesses in the wall of the instrument case, but in all other respects the arrangement of Fig. 4 is identical with the arrangement of Fig. 1, as indicated by the use of corresponding numerals for corresponding parts.

Fig. 4 shows a piston 65 corresponding to the piston 33 of Fig. 1 and mounted in a dashpot cylinder 24a corresponding to the dashpot cylinder 24. The piston 65 has a lower extension 66 of reduced diameter that terminates in a sharp-edged annular flange 67 that is sufficiently close to the internal diameter of the cylinder 24a to have a marked dashpot effect. The usual lift spring 43 in the bottom of the cylinder 24a presses upward against the lower face of the piston 65 below the flange 67. The piston 65 is provided with an inclined dashpot passage 68 corresponding to the dashpot passage 40 of Fig. 1. The dashpot passage 68 is of uniform internal diameter and is controlled at its upper end by a valve member 69 in the form of a suitable ring that slidably embraces the upper plunger shank 31 and rests on the upper face of the piston 65. The valve member 69 is normally held against the upper face of the piston by a suitable valve spring 70 embracing the upper shank 31, the spring being confined between the valve member 69 and a collar 71 that is anchored on the upper shank by a suitable pin 12. The valve member 69 is provided with a relatively small fluid passage 74 that is restricted at its upper end to form a sharp-edged orifice 75. It is contemplated that the fluid passage 74 in the valve member 69 will be continuously in communication with the larger capacity dashpot passage 68, and to insure such communication when the smaller passage is out of registry with the larger passage we provide an intermediary annular groove 76 in the upper face of the piston 65 in communication with both the small passage 74 and the larger passage 68.

The dashpot cylinder 24a has a number of by-pass recesses 77 in its inner cylindrical wall spaced within the range of movement of the dashpot flange 67. In the preferred form of our invention these by-pass recesses 77 are suitably dimensioned annular grooves in the wall of the cylinder 24a, but other forms of recesses may be provided. The by-pass recesses 77 are spaced in accord with the spacing of the constricting ribs 21 in the sleeve insert 12.

When the mud pumps are started up after the piston 65 has completed its upward movement, the spring 70 maintains the valve member 69 in its lowermost position until the pressure created by the mud pump in the mud column rises to a substantial extent and the spring thereby initially retards the downward movement of the piston 65 until the velocity of the mud stream 75 is high enough for an effective first signal wave,

The upward movement of the piston 65 is controlled both by the dashpot effect of the small passage 74 in the valve member 69, the valve member being in its lowermost position, and by the dashpot effect of the piston flange 67. As the piston flange 67 rises upward into successive registry with the by-pass recesses 77 its retarding effect is less but the piston is not materially accelerated at such times because the dashpot effect of the small passage 74 is still effective. On the downward movement of the piston 65, however, the valve member 69 is lifted in the manner of a check valve to permit relatively free flow through the dashpot passage 68, and the rate at which the piston descends is controlled primarily by the clearance for fluid flow around the sharp-edged annular flange 67. After the valve member 69 rises to clear the dashpot passage 68, the piston 65 moves downward at a moderate rate until the piston flange 67 reaches a by-pass recess 77. The by-pass recess 77 provides such ample clearance for fluid flow past the piston flange 67 that the piston spouts in its downward movement for a distance corresponding to the vertical dimension of the by-pass recess. The by-pass recesses are so located that a downward spurt in the movement of the piston 65 occurs shortly before the plunger head 34 of Fig. 1 reaches one of the constricting ribs 21, the plunger head slowing down abruptly at the end of the spurt as the plunger head reaches or approaches registration with the constricting rib. The result of varying the velocity of the downward movement of the piston in the manner described is to increase the intensity of the water-hammer shock and to steepen the front of the indicating pressure wave that passes upward through the mud column.

Another form of our invention shown in Fig. 5 is housed in a special drill stem sub 80 that is like the drill stem sub 10 and in like manner is equipped with a sleeve insert 81 having a series of annular flow-constricting ribs 82. An instrument case 83 is supported in the sub 80 by a spider 84 and is maintained in a centralized position by leaf springs 85 at its upper end.

The upper portion of the instrument case comprises a dashpot cylinder 86 that embraces a hollow plunger 87 and a slidable sleeve 88 in the path of the plunger. The hollow plunger 87 is integral with a piston 90 and the piston 90 is in turn integral with an upwardly extending plunger shank 91 that terminates in a plunger head 92. The piston 90 has a dashpot passage 93 that terminates in a central recess 94 and the interior of the hollow plunger 87 has a conical end wall 95 leading to the central recess. To isolate the dashpot fluid a diaphragm sleeve 96 is connected by an elastic ring 97 at one end to the plunger shank 91 and is connected at the other end to the dashpot cylinder 86 by a split ring 98 engaging a fixed ring 99, the fixed ring being attached to the dashpot cylinder by rivets 100.

The lower interior end of the instrument case 83 provides a recess 102 in which the reduced lower end 103 of a pendulum support 104 is seated and is anchored therein by a cross pin 105. The pendulum support 104 has a head or flange 106 to which an inner cylinder 107 is fixed by pins 108. The inner cylinder 107 is slidably embraced by the previously mentioned slidable sleeve 88 and is integral at its upper end with a bearing block 109 that provides a socket for a ball member 110. A suitable vent passage 111 in the bearing block 75

109 provides fluid communication between the interior of the inner cylinder 107 and the interior of the dashpot cylinder 86 above the bearing block.

Extending upwardly from the ball member 110 is a stop-arm 113 having four annular stop flanges 114 that decrease successively in diameter toward the upper end of the stop-arm. The stop flanges 114 are so dimensioned that at relatively slight inclination from the vertical on the part of the stop-arm 113 the hollow plunger 87 on downward movement will clear all of the stop flanges except the lowermost flange; at somewhat greater inclination of the stop-arm the hollow plunger will abut the next to lowest stop flange; and at maximum inclination indicated by the arrangement the top end 115 of the stop-arm will block the downward movement of the hollow plunger. The inclination of the stop-arm 113 is controlled by a downwardly extending pendulum arm 116 having a relatively heavy pendulum weight 117 and terminating in a locking point 118.

Below the pendulum arm 116 is a locking piston 120 that is slidably mounted in the inner cylinder 107 and is provided on its upper face with a series of concentric locking grooves 121. Preferably the locking grooves are dimensioned to accord with the various angles at which the stop-arm 113 may be effective to arrest the downward movement of the hollow plunger 87. To provide fluid pressure for lifting the locking piston 120 into engagement with the locking point 118 of the pendulum arm we provide fluid communication between the interior of the inner cylinder 107 and the annular space surrounding the pendulum support 104. For example, we provide an axial bore 122 in the pendulum support 104 and a transverse bore 123.

Surrounding the pendulum support 104 is a lift spring 124 for moving the hollow plunger 87 upward to cause the plunger head 92 to traverse the series of constricting ribs 82. The lifting force of the spring 124 is transmitted to the hollow plunger 87 through an annular piston 125 embracing the pendulum support 104 and through the slidale sleeve 88 resting upon the annular piston. Whenever the hollow plunger 87 moves downward by dynamic pressure from the drilling fluid, it forces the annular piston 125 downward against the resistance of the spring 124, and the downward movement of the annular piston displaces liquid through the bores 123 and 122 into the inner cylinder 107 to lift the locking piston 120 against the locking point 118.

To obtain an indication of the bore hole alignment by means of the apparatus shown in Fig. 5, the operator stops the mud pumps for a sufficient interval to permit the lift spring 124 to move the hollow plunger to its uppermost position. It will be noted that the stop-arm 113 is not effective on the upstroke of the hollow plunger. After the required interval of time, in which interval the pendulum becomes stable at its gravitational position, the operator starts the mud pumps and the consequent dynamic pressure against the plunger 92 forces the hollow plunger 87 downward. On the downward movement of the hollow plunger, the plunger head 92 cooperates with the constricting ribs 82 to create the pressure waves in the mud column as heretofore described, and the number of such waves generated by the device will depend upon the range of downward movement permitted by the stop-arm 113, which range of downward

movement, of course, depends upon the alignment of the instrument case 83 relative to vertical. It is to be noted that the initial downward movement of the hollow plunger is transmitted through the slideable sleeve 88 to the annular piston 125 and therefore causes the locking piston 120 to immobilize the stop-arm 113 at or near the gravitational disposition of the pendulum so that the stop-arm is rigid when it is met by the downwardly moving hollow plunger.

It is contemplated that the locking piston 120 will be held in its upper locking position only so long as the annular piston 125 is moving downward and that when the downward movement of the annular piston ceases, the locking piston will drop to its lowermost position to release the pendulum. With this in mind we dimension the annular piston to produce the desired hydraulic effect, but provide enough clearance for reverse leakage when stationary. Further leakage clearance is provided around the locking piston 120 to allow for liquid displacement by the slideable sleeve 88 entering the annular space around the pendulum support 104.

When the hollow plunger is stopped at an intermediate position on its downward movement after a series of signal waves, the locking piston 120 soon retreats to release the pendulum arm 116 and when the operator subsequently resumes drilling rotation, the vibration of drilling jars the stop-arm 113 free of the hollow plunger and the hollow plunger is then driven by the dynamic pressure of the mud stream to its normal retracted position.

It is not necessary in all practices of our invention to restrict or hinder to any substantial degree the downwardly flowing mud stream. For example, as may be understood by referring to Fig. 6, the pressure wave for signalling bore-hole inclination may be generated in a by-pass interconnecting the downwardly flowing mud stream and the upwardly flowing mud stream, the by-pass being open only during signalling periods.

In Fig. 6 a special drill stem sub 128 has an unrestricted passage 129 for carrying drilling fluid to the bit at the end of the drill string. A by-pass 130 provided in the wall of the sub adjacent the mud passage 129 has an inlet port 131 from the mud passage 129 and has an outlet port 132 for communication with the exterior of the sub. The upper end of the by-pass 130 is provided with a suitable valve seat 133 of rubber or other material that cooperates with a valve member 134 in the form of a head on the end of a plunger 136. The by-pass 130 is provided with a series of annular constricting ribs 138 in the same manner and for the same purpose as heretofore described. Immediately below the by-pass 130 is a dashpot cylinder 139 embracing a dashpot piston 140 that is integral with the plunger 136. The dashpot piston 140 has a pair of dashpot passages 141 that are preferably constricted at their upper ends to form sharp-edged orifices. A helical spring 142 for continuously urging the plunger 136 downward is housed in the cylinder 139 in compression between the dashpot piston 140 and an annular flange 143 at the top of the cylinder. A diaphragm 143a is provided to seal off the dashpot cylinder.

Whenever the mud pumps are stopped to interrupt flow through the passage 129 pressure becomes equalized on the opposite sides of the plunger head 134 and the spring 142 has suffi-

cient force at such time to move the plunger 136 downward to carry the plunger head to the lower end of the by-pass 130. Upon resumption of normal mud flow, the mud streaming through the by-pass 130 carries the plunger head 134 upward past the constricting ribs 138 to the normal position against the valve seat 133, and the pressure differential between the mud passage 129 and the exterior of the sub thereafter maintains the plunger head in the closed position until the mud pumps are stopped.

The lower end 144 of the plunger 136 reciprocates in a bore 145 and carries by a ball-and-socket connection a suitable pendulum 146. In the normal raised position of the plunger 136 the upper portion of the pendulum 146 is embraced by the bore 145 to immobilize the pendulum. When the plunger 136 moves downward the pendulum 146 is carried into a pendulum chamber 147 where it is free to seek its gravitational position. The pendulum chamber 147 is successively reduced in diameter to form a series of annular stop shoulders 148 that correspond in number and spacing to the previously mentioned constricting ribs 138.

The operation of the arrangement shown in Fig. 6 is carried out as heretofore described by first stopping and then starting the mud pumps. Once mud circulation ceases the spring 142 moves the plunger downward at a sufficiently slow rate to permit the pendulum 146 to become stable at its gravitational position. The downward movement of the plunger 136 is continued to the full extent if the well bore hole is true, but is interrupted by the pendulum 146 striking a stop shoulder 148 if the bore hole is out of vertical. When the driller starts up the mud pumps, the plunger head 134 is carried upward past the successive constricting ribs 138, thereby generating pressure waves corresponding in number to the range of movement downward previously permitted by the pendulum 146. When the plunger 136 completes its upward movement to reach the normal position shown in Fig. 6 both the plunger and the pendulum are locked against the vibration and thrashing of normal drilling.

In the arrangement shown in Fig. 7 a special sub 150 for the drill string provides an unrestricted downstream passage 151 for drilling mud, a radial by-pass 152 to the exterior of the sub, and a hollow wall 153 to house a plunger control arrangement. The downstream passage 151 is enlarged to form an annular recess 154 in which is slidably mounted a valve sleeve 155 having substantially the same internal diameter as the passage 151. The valve sleeve 155 has a plurality of spaced valve ports 156 positioned to register successively with the radial by-pass 152 as the valve sleeve moves upward or downward. The valve sleeve 155 is connected by an arm 157 to the upper end of a plunger 158 that corresponds with the plunger 136 of Fig. 6.

Fig. 7 shows the plunger 158 integral with a dashpot piston 160 in a dashpot cylinder 161, the piston having two dashpot passages 162 formed with sharp-edged orifices. A diaphragm 162a is provided to seal off the dashpot cylinder. A lift spring 163 acting between the bottom of the dashpot cylinder and the under face of the piston 160 continuously urges the plunger 158 upward. Below the piston 160 and the spring 163 the arrangement is the same as in the lower part of Fig. 6, the plunger 158 being connected as before by a ball-and-socket connection with a pendulum 146 that takes a gravitational position in

a pendulum chamber 147 whenever the plunger 158 moves downward.

During normal drilling operations the friction of the downwardly flowing mud stream on the internal walls of the valve sleeve 155 holds the valve sleeve at the bottom of the annular recess 154 against the opposition of the lift spring 163. When the operator stops the mud pumps to ascertain the current alignment of the bore hole in the vicinity of the bit, the valve sleeve 155 is moved upward by the lift spring 163. When the operator subsequently starts up the mud pumps, the friction of the mud stream in the passage 151 causes the valve sleeve 155 to move downward to bring the valve ports 156 successively into registration with the by-pass 152. If the bore-hole alignment is close to vertical, all of the valve ports 156 will be brought into action to release spurts of the drilling fluid through the by-pass 152. If the pendulum 146 is inclined to any significant extent away from the axis of the drill stem sub 150 the pendulum will encounter one of a series of stop shoulders in the pendulum chamber so that the number of times liquid is discharged through the by-pass 152 will signify the alignment of the bore hole. The opening and closing of the by-pass 152 produces a pressure wave in the mud column that may be detected at the surface of the well.

Our conception of a clinograph mechanism that is moved in one direction by yielding means and is moved in the opposite direction by pressure from the stream of drilling fluid may be incorporated in an arrangement for generating signal waves by impact of metal against metal, the signals being sound waves transmitted to the surface of the well through the metal walls of the drill string. Fig. 8 shows such an embodiment of our invention.

In Fig. 8 a special drill stem sub 170 provides a drilling fluid passage 171, the lower portion of which is enlarged for adequate flow clearance around an instrument case 172. The instrument case 172 is equipped with the usual centering springs 173. The lower portion of the mechanism is broken away in Fig. 8 but is identical with the corresponding mechanism in Fig. 1. Thus the instrument case 172 rests on a spider 17 of Fig. 1 and the lower portion of the instrument case has a progressive series of sharp stop shoulders 28 adapted to be engaged by a head 48 of a pendulum 47.

In the construction shown in Fig. 8, a dashpot piston 175 slidably mounted in a dashpot cylinder 176 is connected to an upwardly extending plunger shank 177 and to a downwardly extending plunger shank 178. The downwardly extending shank 178 has an integral sharp-edged flange 179 and terminates in a ball-and-socket mounting for the aforementioned pendulum 47. The wall of the dashpot cylinder 176 is provided with a series of spaced dashpot recesses 180 for cooperation with the sharp-edged flange 179 in controlling the rate of movement of the plunger assembly that includes the piston 175 and the two plunger shanks 177 and 178.

The piston 175 has one or more down-flow dashpot passages 182 for transmission of the dashpot fluid when the piston moves upward and has one or more up-flow dashpot passages 183 for service when the piston 175 moves downward. An upper ring 184 slidably keyed to the upper shank 177 is adapted to close the up-flow dashpot passages 183 and to place a restricted orifice 185 in registry with each of the down-

flow dashpot passages 182. The upper ring 184 is continually urged toward the piston 175 by a helical spring 186 acting between the upper ring and a collar 187 that is secured to the plunger shank by a suitable pin 188.

In similar manner a lower ring 190 slidably keyed to the lower plunger shank 178 is adapted to close the down-flow dashpot passages 182 and to place in registry with each of the up-flow dashpot passages 183 an orifice 181 of substantially the same cross-sectional areas as the up-flow passage. To urge the lower ring 190 upward against the piston 175, a spring 192 lighter than the upper spring 186 is compressed between the lower ring and the sharp-edged flange 179.

Above the series of dashpot recesses 180 the dashpot cylinder 176 is enlarged in internal diameter to provide an annular shoulder 193 to seat an anvil 194 in the form of a spider with radially disposed legs 195. The anvil 194 surrounds the plunger shank 177 with liberal clearance to avoid interfering with longitudinal movement of the shank. Above the anvil 194 a tubular hammer 196 also surrounds the upper plunger shank 177. The tubular hammer 196 has an inner annular dashpot rib 197 that slidably embraces the shank 177 and the shank 177 has an outwardly extending annular dashpot rib 198 that is in turn slidably embraced by the tubular hammer. The annular space within the tubular hammer 196 between the two dashpot ribs 197 and 198 expands and contracts with longitudinal movement of the shank relative to the tubular hammer and may be aptly termed an annular dashpot chamber. Normally the tubular hammer 196 is supported in a position spaced slightly above the anvil 194 by a helical spring 201 that surrounds the shank 177 in compression between the anvil and the dashpot rib 197. It is apparent that if the plunger shank 177 moves downward at a speed that cannot be accommodated by leakage of dashpot fluid from the annular dashpot chamber 200, the tubular hammer 196 will be carried downward with the shank against the compression of the spring 201, and if the movement is sufficiently rapid the hammer will be carried against the anvil 194 with considerable momentum.

The upward plunger shank 177 has a plurality of radial projections 202 to cooperate with the dashpot cylinder 176 in maintaining the alignment of the plunger assembly, and the shank 177 may also have an enlarged portion 203 of tapered configuration that normally wedges into the top of the tubular hammer 196, as shown in Fig. 8, to hold the tubular hammer fixed against vibration. A diaphragm sleeve 204 to isolate the dashpot fluid is mounted in the previously described manner to bridge the annular space between the plunger shank 177 and the surrounding dashpot cylinder 176. The upwardly extending shank 177 terminates in a streamlined plunger head 205 that is dimensioned to fit into a normally dimensioned portion 206 of the mud passage 171 with slight clearance, say, $\frac{1}{16}$ " to $\frac{1}{8}$ ".

Fig. 8 shows the various parts of the arrangement in normal disposition while mud is being pumped down the drilling fluid passage 171. At such time the pendulum 47 is immobilized in the bottom of the instrument case, as indicated in Fig. 1, the upper ring 184 and the lower ring 190 lie against the opposite ends of the dashpot piston 175, as shown in Fig. 8, the tubular hammer 196 is locked against the anvil 194 by down-

ward pressure from the tapered enlargement 203, and the plunger head 205 is in its fully retracted position in the enlarged portion of the mud passage 171.

When the driller stops the mud pumps to receive an indication of the bore-hole alignment, the lift spring 43 causes the plunger assembly to move upward carrying the plunger head 205 into the normally dimensioned portion 206 of the mud passage 171. The upward movement of the plunger assembly is suitably retarded because while the lower ring 190 yields to permit flow through the down-flow dashpot passages 182, the upper ring 184 maintains its normal closed position, and the downward flow of dashpot fluid through the piston is limited to the capacity of the restricted orifices 185 in the upper ring. As a result of the dashpot effect the plunger assembly rises so slowly that the pendulum 47 shown in Fig. 1 is free to become stable at its gravitational position before the pendulum head 48 reaches the lowermost annular stop shoulder 28. It is to be noted that the limited rate of flow permitted by the restricted orifices 185 keeps the dashpot recesses 180 from accelerating the upward movement of the plunger assembly as the sharp-edged flange 179 passes the recesses. It is apparent that the extent of upward movement of the plunger assembly depends upon the angle taken by the pendulum 47 and therefore varies with the inclination of the drill stem sub 170. Since the range of upward movement of the plunger assembly varies with the inclination of the mechanism, the number of dashpot recesses 180 traversed in the subsequent downward movement of the plunger assembly will also vary with the inclination of the sub 170.

When the operator again starts the mud pumps to resume downward flow of mud through the drill string, the pressure of the mud stream against the plunger head 205 forces the plunger assembly downward against the resistance of the lift spring 43. The lower ring 190 is kept closed by fluid pressure during the downward movement of the plunger assembly, but the upper ring 184 lifts to clear the up-flow dashpot passages 183 to permit relatively rapid flow through the dashpot passages 183. It is to be noted, however, that the spring 186 pressing downward against the upper ring 184 tends to delay the downward movement of the plunger assembly until the pressure of the mud stream has been built up to an effective magnitude.

Since the up-flow dashpot passages 183 are unrestricted and of relatively large flow capacity, the limiting factor in the rate of downward movement of the plunger assembly is the annular clearance around the sharp-edged flange 179, and the normal internal diameter of the dashpot cylinder 176 is so small that normally the sharp-edged flange 179 causes the plunger assembly to move downwardly at a rate well within the leakage capacity of the annular dashpot chamber 200 so that the hammer spring 201 is permitted to hold the hammer 196 in elevated position, notwithstanding the downward movement of the dashpot rib 198 on the plunger shank 177. Whenever the downwardly moving sharp-edged flange 179 reaches one of the dashpot recesses 180, the annular clearance around the sharp-edged flange is increased to a flow capacity commensurate with the flow capacity of the up-flow dashpot passages 183 and the dashpot assembly under the pressure of the downwardly flowing mud stream accelerates or spouts in its downward movement

over a range corresponding to the vertical extent of the dashpot recess. The arrangement is so designed that the successive spouts in the plunger assembly speed, as the sharp-edged flange passes the dashpot recesses, are above the leakage capacity of the annular dashpot chamber 200, and as a result the tubular hammer 196 is forced sharply downward with each acceleration of the plunger assembly and is thereby carried against the anvil 194 with such impact that a readily perceptible sound wave is sent to the surface of the well through the metal of the drill string. Between each acceleration in the downward movement of the plunger assembly, the hammer spring 201 is effective to restore the hammer to its normal spaced relationship to the anvil 194. It is apparent that the number of hammer shocks transmitted to the top of the well will indicate the position at which the pendulum 47 stops the upward movement of the plunger assembly and will thereby indicate the current alignment of the bore hole of the well.

In addition to sending signals to the surface of the well in the form of sound waves transmitted through the metal of the drill string, the arrangement in Fig. 8 also sends signals to the surface of the well in the form of pressure waves in the column of circulating drilling fluid. The pressure waves are created because the plunger head 205 cooperates with the normally dimensioned portion 206 of the passage 171 to retard severely the downwardly flowing stream of drilling fluid, but when the downward movement of the plunger head is permitted to accelerate intermittently by temporary increased flow through dashpot recesses 180, the downwardly flowing drill stream is likewise intermittently accelerated. It is apparent, then, that either the means for creating sound waves or the means for creating fluid pressure variations that are incorporated in the arrangement of Fig. 8 may be relied upon for indicating well-bore deviation from vertical.

In the various forms and practices of our invention exemplified by the above described specific structures, a wide range is permissible in the degree to which the stream of drilling fluid is restricted to create a pressure variation for transmission to the surface of the well and considerable latitude is permissible in the abruptness with which the restriction of flow is accomplished. At one extreme relatively slight restriction in flow may be utilized for signals, the signals being comprehended by noting minor fluctuations in a pressure gauge in communication with the circulating drilling fluid at the surface of the well. At the other extreme the restriction of flow may approach cessation of flow to cause exceedingly large pressure changes in the fluid stream. Again, on one hand, the pressure changes of whatever magnitude may be so gradual as to produce no audible effects, or, on the other hand, may be so abrupt as to create steep-front pressure waves characteristic of water-hammer phenomena. Such water hammer-waves may be of such amplitude as to be readily audible at the surface of the well.

It is not difficult to produce a water-hammer wave of large amplitude; the velocity of the drilling fluid column in a typical drill line is so high that if the column is decelerated relatively rapidly a tremendous water-hammer pressure is developed. The abrupt and relatively severe retardation of flow causes successive laminae of the fluid beginning at the valve or flow-reducing means to be severely retarded with resultant

elastic compression of the fluid and distention of the surrounding pipe, a pressure wave progressing in the fluid stream to the surface of the well at acoustic velocity. In the preferred form of our invention the flow-reducing means is of such design as to retard the column of fluid for periods of short duration. In general the duration of the retardation period is comparable to and preferably shorter than the time required for each water-hammer pressure wave to reach the surface of the well. As soon as the flow-reducing means reopens after the generation of each signal wave, the fluid column is free to unload its accumulated water-hammer pressure as a spurt of fluid downward through the jets in the bit, the unloading wave traveling with acoustic velocity up the column of fluid. In the course of this unloading wave the fluid pressure in the drill pipe drops substantially to normal and the pipe wall contracts to normal dimensions.

It is not essential that the flow-reducing means close extremely rapidly, although if it does the water-hammer wave front will be steep enough to produce an audible signal shock, whereas if it closes more slowly the signal shock will be sub-audible. While the pressure variations produced as described above may be severe enough to produce readily perceptible shock at the surface of the well, in most practices of our invention the signals will be read from some pressure-responsive device such as a common pressure gauge on the mud line.

The various forms of our invention described in specific detail herein will suggest to those skilled in the art various changes, modifications, and substitutions that may be made without departing from the underlying principles of the invention, and we reserve the right to all such changes, modifications, and substitutions that properly come within the scope of our appended claims.

We claim as our invention:

1. A signalling clinograph for service in a well having a channel for a stream of drilling fluid, said clinograph including: a mechanism for subterranean operation in said well, said mechanism being movable in opposite directions and being adapted to move in one of the opposite directions in response to said fluid stream; means cooperative with said mechanism to send a series of signals to the surface of the well when said mechanism moves; and a gravity-responsive deviation-detector to limit the movement of said mechanism in accordance with the degree of the deviation of the well from vertical thereby to vary the number of signals in said series to indicate such deviation at the surface of the well.

2. A signalling clinograph for service in a well having a channel for a stream of drilling fluid, said clinograph including: a mechanism for subterranean operation in said well, said mechanism being movable in opposite directions and being adapted to move in one of the opposite directions in response to said fluid stream; means cooperative with said mechanism to send a series of signals to the surface of the well when said mechanism moves; and a gravity-responsive deviation-detector to limit the movement of said mechanism in accordance with the degree of the deviation of the well from vertical thereby to vary the number of signals in said series to indicate such deviation at the surface of the well, said signalling clinograph as set forth being further characterized in that said mechanism is

surrounded by instrument fluid in a casing immersed in said drilling fluid, said mechanism including means to retard movement of the mechanism sufficiently to permit said gravity-responsive detector to become stable prior to arrival of the mechanism at a point of control, and said mechanism including a flexible diaphragm separating said instrument fluid from said drilling fluid, said diaphragm being adapted to yield for maintaining constant the volume of said drilling fluid displaced by said mechanism.

3. A signalling clinograph for service in a well having a channel for a stream of drilling fluid, said clinograph including: a mechanism for subterranean operation in said well, said mechanism being movable in opposite directions and being adapted to move in one of the opposite directions in response to said fluid stream; means cooperative with said mechanism to send a series of signals to the surface of the well when said mechanism moves; and a gravity-responsive deviation-detector to limit the movement of said mechanism in accordance with the degree of the deviation of the well from vertical thereby to vary the number of signals in said series to indicate such deviation at the surface of the well, said signalling clinograph as set forth being further characterized in that said mechanism and said cooperative means vary the freedom of flow of said fluid stream repeatedly in one operating cycle thereby generating a series of pressure waves in the fluid stream for signals to the surface of the well.

4. A signalling clinograph for service in a well having a channel for a stream of drilling fluid, said clinograph including: a mechanism for subterranean operation in said well, said mechanism being movable in opposite directions and being adapted to move in one of the opposite directions in response to said fluid stream; means cooperative with said mechanism to send a series of signals to the surface of the well when said mechanism moves; and a gravity-responsive deviation-detector to limit the movement of said mechanism in accordance with the degree of the deviation of the well from vertical thereby to vary the number of signals in said series to indicate such deviation at the surface of the well, said signalling clinograph as set forth being further characterized in that said mechanism and cooperative means make successive impacts in one operating cycle for sending sound waves to the surface of the well to serve as said series of signals.

5. A signalling clinograph for service in a well having a channel for a stream of drilling fluid, said clinograph including: a mechanism for subterranean operation in said well, said mechanism having an inherent tendency to move in one operative direction and being adapted to move in the opposite operative direction in response to said fluid stream, whereby the mechanism may be operatively reciprocated by stopping and starting said stream; means cooperative with said mechanism to send a series of signals to the surface of the well when said mechanism moves; and a gravity-responsive deviation-detector to limit the movement of said mechanism selectively at various points in accordance with the amount of the deviation of the well from vertical, thereby to vary said signals to indicate such amount of deviation at the surface of the well.

6. A signalling clinograph for service in a well having a down channel and an up channel for circulating a stream of drilling fluid, said clino-

graph including: walls forming a by-pass between said two channels, said walls being provided with a series of spaced constricting means within said by-pass; means movable in said by-pass and cooperating with said constricting means to vary flow through said by-pass thereby to produce pressure variations in said stream to serve as signals to be detected at the surface of the well; and a gravity-responsive deviation-detector co-expensive with and adapted to control the extent of movement of said movable means and thereby to vary said signals in accordance with the degree of the deviation of the well from vertical.

7. A signalling clinograph for service in a well having a channel for a stream of drilling fluid, said clinograph including: extensile means adapted to be immersed in said fluid stream at a subterranean position; yielding means continuously urging said extensile means to extended disposition, said extensile means being adapted to contract in response to force from said stream in opposition to said yielding means, whereby said extensile means may be caused to extend and contract by stopping and starting flow of said drilling fluid in said channel; stationary means in said channel cooperative with said extensile means to vary the effective cross section of the channel at successive stages in the movement of the extensile means thereby to produce successive pressure variations in the fluid at the surface of the well corresponding in number to the range of movement of said extensile means; and gravity-responsive means to arrest the movement of said extensile means at various points according to the degree of deviation of the well bore from vertical, thereby to vary the number of successive pressure variations to indicate said degree of deviation at the surface of the well.

8. A signalling clinograph as set forth in claim 7 in which means is provided to control the rate of movement of said extensile means relative to said stationary means in a varying manner to accentuate said pressure variations of the fluid.

9. A signalling clinograph for service in a well having a channel for a stream of drilling fluid, said clinograph including: a mechanism for subterranean operation in said well, said mechanism having an inherent tendency to move in one operative direction and being adapted to move in the opposite operative direction in response to flow of said fluid stream, whereby the mechanism may be operatively reciprocated by stopping and starting said stream; stationary means in said channel cooperative with said mechanism to temporarily restrict the effective cross section of the channel at successive spaced points in the movement of said mechanism thereby to produce successive pressure rises in the fluid at the surface of the well corresponding in number to the range of movement of said mechanism; dashpot means to control the rate of movement of said mechanism relative to said stationary means; and a gravity-responsive deviation-detector to arrest the movement of said mechanism at various stages according to the degree of deviation of the well bore from vertical, thereby to vary the number of said successive pressure rises to indicate said degree of deviation at the surface of the well.

10. A signalling clinograph as set forth in claim 9 in which the dashpot means includes an automatic valve to restrict the dashpot flow when a rise in the fluid pressure of said stream tends to accelerate said mechanism whereby the automatic valve prolongs the duration of a pressure

rise caused by said mechanism in cooperation with said stationary means.

11. A signalling clinograph as set forth in claim 9 in which said dashpot means is adapted for automatic increase in dashpot flow to accelerate the movement of said mechanism as the mechanism approaches a position of flow-restricting cooperation with said stationary means, whereby the increased dashpot flow accelerates a pressure

10 rise of the drilling fluid.

12. A signalling clinograph for service in a well having a channel for a stream of drilling fluid, said clinograph including: a signal means having a predetermined maximum signal cycle in the 15 course of which the signal means signals to the surface of the well; fluid-pressure-responsive means adapted to actuate said signal means by energy derived from said stream of drilling fluid; and a gravity - responsive deviation - detector 20 adapted to arrest movement of said signal means selectively at spaced points in said signal cycle in accordance with various predetermined degrees of deviation of the well from vertical whereby the duration of signal sending by the device indicates said degree of deviation.

13. A signalling clinograph for service in a well having a channel for a stream of drilling fluid, said clinograph including: a signal mechanism movable through an operating cycle to repeatedly 30 vary the freedom of flow of said fluid thereby to send a series of pressure signals through the fluid to the surface of the well; means to derive energy from said stream of drilling fluid to actuate said mechanism; and a gravity-responsive 35 deviation-detector to control said mechanism and modify said operating cycle to vary the number of pressure signals in said series in accordance with various predetermined degrees of deviation of the well from vertical.

14. A signalling clinograph for service in a well having a channel for a stream of drilling fluid, said clinograph including: a reciprocating member in said well adapted when moved in one direction to send a plurality of successive signals 45 to the surface of the well; a stationary member in the well; a pendulum mounted on one of said members; stop means carried by the other of said members to cooperate with said pendulum to limit reciprocation of said reciprocating member at selected positions in accordance with the degree of deviation of the well from vertical; yielding means to move said reciprocating means in one direction; and means responsive to said stream to move said reciprocating means in the other direction whereby upon cessation of flow of the drilling fluid said reciprocating means moves in one direction and upon resumption of flow moves in the other direction and whereby the extent of movement of the reciprocating means 55 and therefore the number of said signals varies with the degree of deviation of the well from vertical.

15. A signalling clinograph for service in a well having a channel for a stream of drilling fluid, said clinograph including: extensile means adapted to be immersed in said fluid stream; yielding means continuously urging said extensile means in one direction, said extensile means being adapted to move in the opposite direction 65 in response to said stream in opposition to said yielding means whereby said extensile means may be caused to move in one direction by stopping the flow of said drilling fluid and in the opposite direction by resuming flow of the drilling fluid; stationary means in said channel cooperative 70

with said extensile means to vary the effective cross section of the channel repeatedly in the course of movement of the extensile means in one direction, thereby to produce successive pressure signals in the drilling fluid; and a gravity-responsive deviation-detector adapted to selectively limit the range of movement of said extensile means in accordance with the degree of deviation of the well bore from vertical, thereby to vary said pressure signals to indicate said degree of deviation.

16. A signalling clinograph for service in a well having a channel for a stream of drilling fluid, said clinograph including: means forming a portion of said channel; a first means reciprocative in the well cooperative with said channel-forming means when moved in one direction to alternately increase and decrease the effective cross section of the channel repeatedly to create a series of signal waves in said stream of drilling fluid, said first means being adapted to move in one direction automatically when flow of said drilling fluid ceases and to move in the other direction automatically in response to flow of the drilling fluid; a second means stationary in the well; a gravity-responsive deviation-detector mounted on one of said first and second means; and stop means fixed relative to the other of said first and second means cooperative with said deviation-detector to limit at selected positions the movement of said first means according to the degree of deviation of the well from vertical whereby such deviation is indicated by the number of signal waves in said series.

17. A signalling clinograph for service in a well having a channel for a stream of drilling fluid, said clinograph including: a reciprocating member in said well adapted when moved in one direction to send a plurality of successive signals to the surface of the well; a stationary member in the well; a gravity-responsive deviation-detector mounted on one of said members; stop means fixed relative to the other of said members cooperative with said deviation-detector to limit at selected positions the movement of said reciprocating member according to the degree of deviation of the well from vertical whereby such deviation is indicated by the number of said successive signals; and a retaining means responsive to movement of said reciprocating member to immobilize the deviation-detector automatically while said deviation-detector is out of engagement with said stop means during normal flow of said drilling fluid.

18. A signalling clinograph for service in a well having a channel for a stream of drilling fluid, said clinograph including: a signal means having a maximum signal cycle in the course of which the signal means signals to the surface of the well; fluid-pressure-responsive means exposed to said stream for actuation of said signal means, said fluid-pressure-responsive means having a normal limit position maintained in response to the velocity load of said stream permitting flow of said stream adequate for normal drilling operation, said fluid-pressure-responsive means having an inherent tendency to move towards an alternate limit position whereby the fluid-pressure-responsive means moves towards said alternate limit position automatically upon cessation of such flow; and a gravity-responsive deviation-detector adapted to arrest movement of said signal means selectively at spaced points in said signal cycle in accordance with predetermined degrees of deviation of the well from vertical

whereby the duration of signal sending by said signal means indicates said degree of deviation.

19. A signalling clinograph for service in a well having a channel for a stream of drilling fluid, said clinograph including: movable means in the well exposed to said stream, said means having a normal limit position permitting flow of said stream adequate for normal drilling operation and being adapted to move automatically towards an alternate limit position upon cessation of such flow, said means being movable in the direction from said alternate position towards said normal position in response to flow of said stream and being adapted to repeatedly vary the freedom of flow of the stream in the course of such movement thereby to create a series of pressure signals in the fluid; and a gravity-responsive deviation-detector to limit the movement of said movable means in the direction of said alternate limit position in accordance with the degree of deviation of the well from vertical thereby to vary the number of said pressure signals to indicate said degree of deviation.

20. In a device of the type described for use in a drill stem or the like, a stepped member and a pendulum movable relative to each other in a direction longitudinally of said drill stem to cause engagement of said pendulum with a portion of said stepped member depending on the inclination of said drill stem, and means for indicating at the upper end of said drill stem the portion of said stepped member engaged by said pendulum.

21. In a device of the character described for use in a drill stem or the like, a member movable in said drill stem while fluid is being forced therethrough, cooperating flow-constricting means on said member and within said stem, said means being relatively spaced in the direction of movement of said member and adapted to intermittently throttle such flow of fluid during the time said member is moving, and gravity responsive means for limiting the extent of such movement of said member in accordance with the inclination of said drill stem from the vertical.

22. In a device for indicating the inclination of a drill stem or the like, a housing adapted to be located in said drill stem, an inclination indicating mechanism disposed in said housing and including a plunger adapted to project from said housing, a lubricating and protecting fluid substantially filling said housing for lubricating and protecting said mechanism from the action of fluid flowing through said drill stem about said housing, and a flexible member secured to a portion of said housing and embracing said plunger whereby the pressure of fluid in said housing and of fluid flowing through said drill stem will be substantially equalized at all times.

23. In a device for indicating the inclination of a drill stem or the like, a housing adapted to be disposed in said drill stem, an inclination indicating mechanism disposed in said housing and dependent on variations of pressure in fluid flowing through said drill stem for its operation, said mechanism including a plunger adapted to be projected from said housing and forming with said housing an annular opening, a lubricating and protecting fluid substantially filling said housing for protecting said mechanism from contact with fluid in said drill stem, and a flexible member connected to said housing and embracing said plunger to close said opening, whereby the pressure of said protecting and lubricating fluid

will vary with the pressure of the fluid in said drill stem.

24. A signalling clinograph for service in a well having a channel for drilling fluid, said clinograph including: a housing adapted to be immersed in said drilling fluid in said channel, said housing containing a body of fluid for lubrication and for protection from said drilling fluid; a mechanism mounted in said housing, including means partially in the housing and partially immersed in said drilling fluid and adapted for movement relative to the housing in response to starting and stopping of flow of the drilling fluid through said channel; means cooperative with said mechanism to send a series of signals to the surface of the well when said mechanism moves; a gravity-responsive deviation-detector to limit the movement of said mechanism in accordance with the degree of deviation of the well from vertical, thereby to vary the number of signals in said series to indicate such deviation at the surface of the well; and a flexible member comprising a portion of said housing movable to compensate for displacement of said lubricating fluid in said housing in response to relative move- 25

ment of said relatively movable means whereby the pressure of lubricating fluid in said housing and the pressure of said drilling fluid around the housing are substantially equalized at all times.

Certificate of Correction

Patent No. 2,435,934.

February 10, 1948.

FRED M. VARNEY ET AL.

It is hereby certified that errors appear in the printed specification of the above numbered patent requiring correction as follows: Column 6, line 48, for the word "plunged" read *plunger*; column 19, line 10, for "co-expensive" read *co-extensive*; column 21, line 64, for "load" read *head*; and that the said Letters Patent should be read with these corrections therein that the same may conform to the record of the case in the Patent Office.

Signed and sealed this 4th day of May, A. D. 1948.
